Primary Examiner — Brett Miller*Assistant Examiner* — Rani J Abdallah(74) *Attorney, Agent, or Firm* — Quarles & Brady LLP(57) **CLAIM**

The ornamental design for an actuator overcap, as shown and described.

DESCRIPTION

FIG. 1 is an isometric view of a top, front, and right side of an ornamental design for an actuator overcap;

FIG. 2 is an isometric view of a top, rear, and left side of the actuator overcap of FIG. 1;

FIG. 3 is a front elevational view of the actuator overcap of FIG. 1;

FIG. 4 is a rear elevational view of the actuator overcap of FIG. 1;

FIG. 5 is a left side elevational view of the actuator overcap of FIG. 1;

FIG. 6 is a right side elevational view of the actuator overcap of FIG. 1; and,

FIG. 7 is a top plan view of the actuator overcap of FIG. 1.

1 Claim, 5 Drawing Sheets(56)
